UNITED STATES PATENT OFFICE.

JOHANNES RUTHS, OF DJURSHOLM, SWEDEN.

STEAM PLANT.

Original application filed December 27, 1924, Serial No. 758,438, and in Germany and Sweden January 14, 1924. Divided and this application filed September 29, 1925, Serial No. 59,379.

- This application is a division of my co-pending application Ser. No. 758,438, filed Dec. 27, 1924, which has matured into Patent Number 1,666,426, April 17, 1928.
- 5 My invention relates to steam plants, and more particularly to steam plants wherein there is a variable steam consumption.
- 10 My invention involves a novel manner of generating steam of high pressure, for example from 1,500 to 3,000 pounds per square inch, or higher, and to generate steam substantially in proportion to the demand, and at any desired temperature, but independently of heat supplied to the plant in the form of fuel so that the generating of heat is independent of steam consumption. For example, by this means, a constant firing of boilers may be obtained while at the same time the steam generation and steam consumption vary considerably.
- 15 Another purpose of my invention is to produce a novel means for superheating steam, and to provide a highly efficient system wherein high pressure steam is used and superheated for different purposes.
- 20 I have discovered that it is possible to build a practical high pressure boiler operating at pressure higher than those yet acquired in practice by means of an indirect system of generating the high pressure steam with the help of a medium of high boiling point and having high temperature at low pressure, the said medium consisting of phenanthrene or a similar liquid. I utilize such liquids also to store heat as set out herein.
- 25 I utilize these liquids also to superheat steam and more particularly as shown herein to superheat steam between stages of a turbine.
- 30 With these and other objects my invention consists in the matter herein described and more particularly pointed out in the appended claims, reference being had to the accompanying drawings which illustrate some forms of my invention.
- 35 In the drawing, Fig. 1 shows a steam plant illustrating several phases of my invention part of which is taken substantially on line 1—1, Fig. 2.
- 40 Fig. 2 is a section through a turbine taken on the line 2—2 of Fig. 1 showing details of the preferred manner of superheating steam between stages.
- 45 Fig. 3 shows diagrammatically a modified form of accumulator for carrying out the present invention.
- 50 Fig. 4 is a diagram showing corresponding boiling points and pressure of various liquids illustrating advantages of the present combination.
- 55 In Fig. 1, 5 indicates a boiler of any suitable construction which may utilize any desired means of heating.
- 60 For the purpose of illustration, I have shown what is ordinarily termed a "water-tube" boiler comprising "water tubes" 6, and a transverse "steam-and-water drum" 7. The boiler, which may be termed a primary boiler, is shown as fired by means of pulverized fuel supplied by means of burner 8. Air is supplied through ports 9, and in the illustration shown is preheated by means of a rotary air preheater 10 of known construction, and comprising a rotor 11 filled with 75 regenerative material 12, which rotor rotates partly in a passage 13 for fresh air to be heated, and partly in a passage 14 for the hot products of combustion, said products of combustion giving off heat to the 80 rotor, the two passages 13 and 14 being separated by partition walls 15.
- 85 In this boiler 5 the above-mentioned liquid of high boiling point, in referring to which, for convenience I will hereinafter use the name of the preferred liquid, phenanthrene, is vaporized in a manner similar to that in which steam is generated from water, and the vapor generated is conducted through conduits 16, 17, 18 and 19 into 90 the liquid space of the accumulator 20. Check valve 121 is provided to prevent return of liquid from the accumulator into the primary boiler piping. Phenanthrene boils under atmospheric pressure at 640° F. 95 wherefore it is seen that a very high temperature in the liquid and vapor in boiler 5 and accumulator 20 is obtained.
- 100 The accumulator 20 consists of a large receptacle having a liquid space 21 and a vapor space 22 and is well insulated as indicated at 23.
- 105 This accumulator is designed with respect to the heat consumption of the plant and it

is built of such size that it can store sufficient heat, and give off sufficient heat, so that the supply of heat, as for example the fuel supply to boiler 5, can be made independent of the steam consumption.

In the steam space of the accumulator are positioned one or more elements 24 which constitute the high pressure steam generator of the plant. I have found that a greatly improved heat transfer is effected with the high pressure elements placed in the steam space than if they are submerged in the liquid.

In the form shown these elements, which might be termed a secondary boiler, consists of a series of pipe-coils placed in a vapor drum 26, which is connected to the main body of the accumulator by means of the connections 27.

Water is supplied to the high pressure elements 24 through conduit 28 at substantially the pressure at which steam is to be generated. The relatively cold water entering the elements 24 absorbs heat through the walls of the elements and condenses the phenanthrene vapor in the vapor drum 26, the condensate returning to the liquid space of the accumulator.

In operation, phenanthrene vapor is continually formed from the liquid in the lower part of the accumulator, due to a slightly lower pressure prevailing in the vapor space than corresponds to the temperature of the liquid, which lower pressure is caused by the cooling effect of the water in coils 24. The vapor formed disengages itself at the liquid surface, rises through the outer connections 27, is condensed on coils 24, falls down into the lower part of drum 26 and is returned to the liquid space 21 through central connection 27. From elements 24 steam is conducted through conduit 31 to means for consuming steam such as turbine 30.

Turbine 30 is a high pressure non-condensing multiple stage turbine operating for example between 2000 and 300 lbs. per square inch, and discharging into intermediate pressure conduit 32 from which consumers as, for example, digester 33 may receive steam. This turbine is provided with novel means for inter-stage superheating more fully described hereinafter.

Connected to the conduit 32 is a heat-exchanger 34 comprising an inner coil of pipe 35 and a casing 36. Steam passes from the conduit 32 through the coil 35 and into conduit 37, which supplies steam to a multiple stage condensing turbine 40 operating from about 300 lbs. to condenser pressure.

Phenanthrene vapor is supplied to the casing 36 from the vapor space of accumulator 20 by means of conduits 38, 39 and 41, and, surrounding the coil 35, heats the same to raise the temperature of the steam passing through so that said steam is super-

heated. To regulate the supply of phenanthrene vapor passing into exchanger 34, I have shown a valve 42, which may be controlled by means of a thermostat 43 placed in the conduit 37, and operating to maintain a constant temperature in conduit 37.

The thermostatic control may, for example, consists of a bulb filled with liquid and connected with a tube 122 which is also connected with a diaphragm chamber 123, so that when the temperature rises, the liquid expands and moves diaphragm 124 downwards so that valve 42 more or less closes, limiting the flow of phenanthrene vapor into casing 36. Phenanthrene leaves exchanger 34 through conduit 44 and enters the water economizer 45 in which feed water for the high pressure elements 24 is pre-heated. In this economizer 45, I preferably decrease the temperature so that the phenanthrene is a liquid of low temperature, for example 250° F.

Pump 46 driven by motor 47 withdraws phenanthrene from economizer 45 through conduit 48 and pumps the same through conduit 49 into the phenanthrene economizer 50 which is heated by means of products of combustion leaving the boiler 5 through flue 51 controlled by the damper 52. From economizer 50 the phenanthrene passes through conduits 53 and 56 into the liquid space of drum 7.

The low pressure phenanthrene which is conducted to the accumulator 20 and therein condensed is returned from the liquid space of the economizer to the liquid space of the primary boiler by means of motor driven pump 54 and conduits 55 and 56. The pump 54 may be controlled in any manner so that a proper level of liquid is maintained in boiler 5. The liquid level in the accumulator may vary quite considerably depending on the difference between consumption and generation.

Several boilers may supply one accumulator. To illustrate this I have shown a second primary boiler 60 supplying phenanthrene vapor to conduit 17. In this case I have shown a horizontal return tubular boiler. It is, of course, understood that the present invention is independent of the type of primary boiler used. If valve 125 is closed and valve 126 open, the primary boilers 5 and 60 supply the accumulator through the same piping. If valve 126 is closed and valve 125 open the supply from these boilers is independent. I have shown this to illustrate a slightly different mode of operation of these different types of boilers which might be preferable in some cases. Where the pressure changes in the accumulator are rather large, it is preferred to place an overflow valve, indicated at 127, between the small liquid space boiler 5 and the accumulator which valve will operate to 130

maintain a constant pressure in boiler 5. However, with a boiler of large cubic contents such as 60, the pressure may more readily vary with the pressure in the accumulator, in which case the overflow valve may be omitted.

Furthermore, since it requires less time to fire up the type of boiler shown at 5, it may be advantageous to operate one or more 10 boilers like 60 continually and hold one or more boilers of the type of boiler 5 in reserve.

Means are shown whereby liquid can be kept in constant circulation between the 15 accumulator and boiler 60. This comprises a conduit 57 including a pump 58 driven by motor 59 and a conduit 61 including a motor driven pump 62. The first conduit with its pump is designed to conduct liquid 20 phenanthrene from the boiler to the liquid space of the accumulator. The second conduit with its pump is designed to conduct liquid from the accumulator to the liquid space of the boiler. By this means a uniform 25 distribution of heat and a better operation of the accumulator may be obtained. The conduit 57 with its pump is also extremely useful in firing up the boiler 60; especially when a liquid such as phenanthrene 30 is used, since phenanthrene expands very rapidly as its temperature is raised. Thus, in firing up a boiler, it has been found necessary to gradually remove phenanthrene from the boiler as the temperature rises 35 in order to maintain a water-level within the boiler. This may be done as shown in the present instance by conducting the liquid through conduit 57 and into the accumulator.

With a system designed as herein set out 40 it becomes very practical to effect inter-stage superheating by means of the low pressure high boiling point phenanthrene.

I have shown two different ways of doing this. In the instance of the turbine 45 phenanthrene vapor is conducted to a superheat chamber 65 in which superheat tubes are arranged to be heated by means of the vapor or by the liquid formed by condensation of the same. From the high pressure stage H of turbine 40 the steam passes through conduit 66 and into header 67 from which it passes through U-tubes 68 into header 69 and through conduit 70 into the intermediate stage M. From the intermediate stage M the steam passes through conduit 71, into header 72, through U-tubes 73 into header 74 and through conduit 75 into the low pressure section L. From the low pressure section steam is conducted to condenser 76 from which the condensate is conducted by means of pump 77 into hot-well 78. From the hot-well 78 water is conducted through conduit 79 and pump 80 65 into the water space of the economizer 45.

The superheat tubes 68 and 73 are, as is thus seen, arranged in parallel to be heated by the phenanthrene. In the superheat chamber the phenanthrene may be partly condensed. The phenanthrene, whether 70 vapor or liquid is conducted from the superheat chamber through conduit 81 to economizer 45 where heat is extracted in raising the temperature of feed-water. If necessary or desirable, pump 82 may be inserted 75 in conduit 81 to help in obtaining this result.

In the instance of the turbine 30 the inter-stage superheating is effected in chambers 80 forming a part of the turbine, which chambers are arranged around the outer casing of the turbine and preferably contain tubes through which phenanthrene circulates.

Steam is supplied to the turbine from conduit 31 through conduit 90. Admission to the first wheel 93 is controlled by a mechanism 92 comprising a series of valves operating successively in response to speed of the turbine acting through the agency of centrifugal governor 91, this control being 90 known. As is obvious, other forms of control may be used in accordance with this invention. Steam after passing through the blades of the first wheel enters channels 94 which communicate with chambers 95. 95 (Fig. 2). Each of these chambers is bordered by circular portions 96 of the main turbine casing. Part of these circular portions 96 comprises covers 97 which are secured by means of stud bolts 130 so that they may be readily removed to gain access to chambers 95. Each of the chambers 95 is also bordered by two tube plates 98 between which and through holes of which tubes 100 extend and into which the tubes 105 are expanded or otherwise secured as by welding. Between tube plates 98 are formed an upper inlet chamber 101, two side chambers 102, 103 and a lower discharge chamber 104. Chambers 101, 102, 103 and 110 104 are in communication through the interiors of tubes 100. The turbine casing is made in parts which are coupled together at the sides. Tube plates 98 are secured to ledges 105 forming part of the casing. The 115 whole is arranged so that there is no communication or leakage between the space comprising chambers 101, 102, 103, 104 and the insides of tubes 100 on the one hand and the space comprising chambers 95 surrounding tubes 100 on the other hand.

The parts are so arranged that the covers 95 may be removed and the tubes 100 and tube plate 98 removed as units for purposes of cleaning and repair.

The steam in passing through chambers 95 around tubes 100 is caused to be deflected by baffle plate 106 to assure an intimate contact of the steam with tubes 100.

Phenanthrene vapor is admitted to cham- 130

ber 101 through pipe 107 controlled, for example by valve 108. This vapor then passes to both sides of the turbine, through upper tubes 100, through chambers 102 and 5 103, in parallel, through the lower groups of tubes 100 and into chamber 104 from which the phenanthrene passes through conduits 109 and 110 into economizer 45.

The phenanthrene, as is understood from 10 the above description superheats the steam as it passes from one wheel to the next.

The turbine is shown as driving a generator 111, with exciter 112 through reduction gear 113, although it may drive any 15 apparatus.

Other superheating chambers 114 and 115 are shown between other stages of the turbine. The arrangement of these may be varied according to circumstances.

20 By means of this invention I am able to produce steam of hitherto unacquired pressure and produce the same without having that part of the boiler which is under high pressure in contact with flames while at the 25 same time heat is accumulated in liquid of low pressure so that the heat production need not follow the curve of heat consumption and the mode of heat production is simplified.

30 The advantages of high pressure are well known. High pressure gives a more economical plant since practically no more heat need be applied to obtain higher pressure. Fuel consumption is less per k. w. h. at 35 higher pressure. The advantage of inter-stage superheating in raising the efficiency of turbines and the longer life of turbine parts thereby acquired are known. The value of heat accumulation so that heat generation is independent of heat consumption 40 is known. I have herein described novel means for producing these advantages and for combining them in a manner that gives greater efficiency than has hitherto been possible.

45 Boilers have previously been built to carry pressure up to 1200 and 1500 pounds per sq. inch pressure but in these constructions all of the boiler has been at the pressure of generated steam giving an undesirable arrangement liable to leakage and other faults. My high pressure boiler is confined to one or more small elements preferably coils which give great strength without parts liable to leakage since such joints as are necessary can be made tight without difficulty. Furthermore I place the high pressure element in the vapor space of the accumulator thus taking advantage of the higher 50 rate of heat transfer obtained by the condensation of the vapor. Phenanthrene vapor condenses on the tubes, falls down into the liquid space and further vapor is drawn to the tubes to be condensed, thus obtaining 55 a constant circulation of heat transmit-

ting medium past the condensing tubes. In this manner I am able to reduce the high pressure steam generating surface to a very small percentage of the heating surface of the primary boilers 5 and 60.

70 The operation of the plant is obvious from the above description. Suppose, for example, that the load in circuit 120 increased. Turbine 30 being the one equipped with a speed governor, will feel the increased load 75 and operate to add power to the circuit by opening valve mechanism 92 to receive more steam and convert the same into power. More water must then be supplied to high pressure generating elements 24 to compensate for the increased demand.

80 This condenses more phenanthrene vapor in the accumulator. If more vapor is condensed than the quantity entering the accumulator, the pressure in the phenanthrene 85 space thereof falls in a manner similar to a steam accumulator filled with water. However, there are many advantages in the accumulator of the present application over the ordinary steam accumulator. Here the 90 pressure of steam supplied can be constant regardless of varying pressure in the accumulator. Furthermore the heat accumulated per cubic foot is about double that of the accumulator containing water. This is 95 evident from the showing in Fig. 4 which is a diagram showing the corresponding temperature and pressure values of boiling of various liquids. Suppose no vapor is led from boiler 5 to the accumulator and only 100 the accumulated heat in the accumulator is utilized and that the pressure in the accumulator is 100 pounds per square inch. The corresponding temperature is about 900° F. Now water is led into coils 24 and phenanthrene vapor condensed until the pressure in the 105 accumulator is atmospheric. The temperature drop is then about 250° F. The temperature drop in water between the same values of pressure is about 125° F. Consequently it is seen that for these pressure values only one half as large an accumulator 110 is necessary with phenanthrene as with water. No accumulators are built outside the pressures here indicated wherefor this 115 advantage may be said to be present in all cases.

120 In many cases it will make a cheaper construction, especially with the use of media which are more expensive than phenanthrene if the accumulator or the boilers are not only filled with a suitable liquid but also with solid material such as cast-iron, ores, slacks of blast furnaces and certain kinds of stones. This is indicated by reference character 131 125 in Fig. 3.

125 Further in the embodiment illustrated in Fig. 3 the steam generated in boilers 5 or 60 is directly supplied to the vapor space of the accumulator and condensed by the 130

liquid of the accumulator which for this purpose is drawn from the lower part of the accumulator by pump 117 through conduit 118 and forced through conduit 119 into the 5 vapor space.

In Fig. 1 are shown valves 132, 133 and 134 and a by-pass conduit 135, illustrating that the phenanthrene may heat or superheat in series or in parallel. When 10 valve 134 is closed, phenanthrene is supplied in parallel to heat-exchanger 34 and superheat chamber 65. When valve 134 is open and valves 132 and 133 are closed phenanthrene passes in series through heat ex- 15 changer 34 and superheat chamber 65. The latter arrangement offers some advantages in some cases in obtaining more heat from the phenanthrene especially in case it is inconvenient to couple cooling apparatus such 20 as the economizer 45 to the heat-exchanger.

Turbine 40 drives generator 136 coupled to circuit 120 in parallel to generator 111.

Overflow valve 137 controls delivery of steam to turbine 40. Turbines 30 and 40 25 may be regarded as one machine with an extraction to digester 33, turbine 40 taking the steam not used by the extraction consumer and being so constructed that it can receive all steam delivered to the same and 30 convert it into power. When consumer 33 draws a large quantity of steam, the supply to turbine 40 is momentarily decreased wherefor the power delivered by the same to circuit 120 is decreased, wherefor the de- 35 creased revolutions of turbine 30 will cause a response of governor 91 to send more steam through turbine 30.

Although I have described phenanthrene as the preferred liquid, it is to be understood 40 that the invention is not limited thereto but may also use other liquids such as naphthalene.

While I have described what is to my 45 mind the preferred means for carrying out my invention, it is to be understood, that my invention is not limited to the arrangement of parts herein shown nor the operations therein involved but by the scope of the appended claims considered in light of 50 the prior art.

I claim:

1. A turbine comprising a plurality of 55 wheels, means forming part of said turbine for superheating the steam passing between said wheels, an accumulator containing a liquid of high boiling point in boiling condition and means to conduct vapor of said liquid from said accumulator to the first mentioned means.

2. A turbine comprising a casing, a cham- 60 ber formed on the periphery of said casing, plates at each end of said chamber, tubes extending between said plates, means to conduct steam through said chamber, an accumu- 65 lator containing a liquid of high boiling

point in boiling condition and means to conduct vapor of said liquid from said accumulator to and through said tubes.

3. A turbine comprising a casing, a chamber in said casing, a wheel in said turbine, 70 means to deliver steam from said wheel into said chamber, a second wheel in said turbine, means to deliver steam from said chamber to the second wheel, means to deflect the steam flowing through said chamber, a series 75 of tubes extending through said chamber, an accumulator containing a liquid of high boiling point in boiling condition and means to conduct vapor of said liquid from said accumulator to and through said tubes. 80

4. A turbine comprising a casing, a chamber in said casing, a wheel in said turbine, means to deliver steam from said wheel into said chamber, a second wheel in said turbine, means to deliver steam from said chamber to said second wheel, a baffle plate in said chamber to deflect the steam flowing there- 85 through, tube plates forming walls for said chamber, tubes extending between said tube plates, an accumulator containing a liquid of 90 high boiling point in boiling condition and means to conduct vapor of said liquid from said accumulator to and through said tubes.

5. A turbine comprising a casing, a cham- 95 ber forming part of said casing and being curved in an arc, the center of which is sub- stantially the turbine axis, tube plates at the ends of said chamber, tubes extending between said tube plates, an accumulator 100 containing a liquid of high boiling point in boiling condition and means to conduct vapor of said liquid from said accumulator to and through said tubes.

6. In a steam plant, in combination, a primary boiler containing and vaporizing 105 phenanthrene, an accumulator connected therewith and accumulating heated phenanthrene therein, and having a liquid and vapor space, a high pressure steam generating element situated in said vapor space, means to supply water thereto, a turbine having a plurality of stages, means to conduct steam from said high pressure steam generating element to said turbine, a chamber, means to conduct steam from one of said stages of 110 said turbine into said chamber, a heating element in said chamber, means to conduct phenanthrene from said accumulator through said heating element to superheat the steam conducted to said chamber, and means to 115 conduct steam from said chamber to another of said stages of said turbine. 120

7. In combination, a consumer, a heat ex- 125 changer situated near said consumer and having a conduit through which steam passes, means to supply said steam to said consumer, a space in said heat exchanger for the reception of a vapor of low pressure and high temperature, means to produce said vapor, an accumulator for accumulating 130

said vapor connected to said producing means, and means to conduct vapor from the accumulator to said space.

8. In combination, a consumer, a heat exchanger situated near said consumer and having a conduit through which steam passes, means to supply said steam to said consumer, a space in said heat exchanger for the reception of a vapor of low pressure and 10 high temperature, means to produce said vapor, an accumulator for accumulating said vapor connected to said producing means, means to conduct said vapor from said accumulator to said space and automatic means 15 to control the flow of said vapor into said space in response to the temperature of steam supplied to said consumer.
9. In a steam plant, in combination, a primary boiler containing and vaporizing 20 phenanthrene, an accumulator connected therewith and accumulating heated phenanthrene therein, and having a liquid and vapor space, a high pressure steam generating element situated in said vapor space, 25 means to supply water thereto, a motor,

means to conduct steam from said high pressure steam generating element to said motor, a chamber, means to conduct steam from said motor into said chamber, a heating element in said chamber, means to conduct 30 phenanthrene from said accumulator through said heating element to superheat the steam conducted to said chamber, and means to conduct steam from said chamber to said motor.

10. In combination, a source of steam, a steam consumer, a heat exchanger, a second steam consumer, means for conducting steam from said source in series through said first consumer, said heat exchanger, and said 40 second consumer, means to produce a vapor of low pressure and high temperature, an accumulator for accumulating said vapor, and means to conduct high temperature vapor from said accumulator to said heat 45 exchanger to reheat the steam passing therethrough.

In testimony whereof I hereunto affix my signature.

JOHANNES RUTHS.
